J. HOJNOWSKI

DEVICE FOR HOLDING THE MOVABLE JAWS OF COUPLERS OPEN

Filed Dec. 24, 1926

Patented June 28, 1927.

UNITED STATES PATENT OFFICE.

JAKOB HOJNOWSKI, OF NEKOOSA, WISCONSIN.

DEVICE FOR HOLDING THE MOVABLE JAWS OF COUPLERS OPEN.

Application filed December 24, 1926. Serial No. 156,861.

My invention relates to improvements in the couplings of railroad cars, and particularly in devices for holding the movable jaws of such couplers in open position for the ready reception of the coupling member of the other car, allowing a positive engagement of the coupling clutches or members for the reception of the coupling bolts etc.

It is the principal object of my invention to provide a device of this type of extremely simple and therefore inexpensive construction, which yet is durable and efficient in its operation.

Another object of the invention is the provision of a device of the above described type suitably formed by strong wire spring members for holding the movable jaws of the couplings in open position, whereby either one spring member or a plurality of such springs may be used.

These and other objects and advantages of my invention will become more fully apparent as the description thereof proceeds, and will then be specifically defined in the appended claims.

In the accompanying drawing, forming a material part of this disclosure:

Fig. 1 is a plan view of a car coupling member having its movable jaw kept in open position by a device constructed according to my invention.

Fig. 2 is a side view thereof.

Fig. 3 is a view, similar to Figure 1, of a modified form of my device.

Fig. 4 is a side view thereof.

As illustrated in Figures 1 and 2, the draw bar of a coupler, designated 10, has an enlarged head 11 equipped with a stationary jaw 12, and a movable or swinging jaw 13, the inner end of which is pivotally secured to the head by a pin or bolt 14 having an outer head 15 and extending at both of its ends beyond the plane of the head.

A strong spring wire 16 or the like is guided intermediate its ends about a pin or bolt 17 and is held in position by means of a plate 18 and a nut 19 in engagement therewith and threaded upon the end of the bolt.

The outer ends of the wire 16 are suitably bent and guided about the projecting ends of the pin or bolt 14, as indicated at 20 and 21, respectively, and the angularly bent ex-

treme ends of the wire 16, are designated 22 and 23 respectively and engage laterally into a bore 24 in the jaw 13 at opposite sides thereof for a sufficient distance.

It will be clear that the spring 16 will at all times hold the coupling jaw 13 open for the introduction of the coupling member of an adjoining car so that the coupling clutches may engage and be held in engagement by the customary coupling pin. As any of the customary coupling clutches and pins may be used with my device, and as they do not form an object of the present invention they need not further be specifically described.

In the modified form of my invention illustrated in Figures 3 and 4, two separate spring members 26, 27 are used for holding the movable jaw of the coupling open, and have their ends wound about pins or bolts 28 projecting from the head 11 and held in place by means of nuts 29 engaging plates 30.

Intermediate their ends the springs are wound about the ends of a pin or bolt 14 headed at one end as at 15, and projecting beyond the head 11, as indicated at 31, 31' respectively. The extreme outer ends of the springs 26, 27 are angularly bent as above described with respect to the preferred form, and engage into a bore 24 of jaw member 13 at opposite ends.

The operation of my improved device for holding the swinging jaws of car couplers open at all times will be entirely clear from the above description, and it is to be understood, that such changes as come within the scope of the appended claims may be made in the construction of my device without departure from the gist of the invention.

Having thus described my invention, what I claim as new and desire to secure by Letters Patent is:

1. A device of the class described comprising a strong wire spring having an intermediate bend, a bolt and nut for securing the spring at the bend to the head of a coupler, a pin transversely held in the coupler head having the spring wound about its ends, and means for anchoring the outer extreme angularly bent ends of the wire in the swinging jaw of the coupler for holding the same open.

2. A device for holding the swinging jaws of car couplings in open position comprising a spring, a pin in the head part of the coupling about which said spring is wound intermediate its ends, a nut for holding the spring in position on said bolt, a cross-pin on said coupling head extending beyond the plane thereof about which said spring is

wound, said swinging jaw having a cross-bore in which the ends of said spring are anchored.

Signed at Nekoosa in the county of Wood and State of Wisconsin this 10th day of December A. D. 1926.

JAKOB HOJNOWSKI.
